US0D1087152S

(12) **United States Design Patent** (10) **Patent No.:** **US D1,087,152 S**
(45) **Date of Patent:** **** Aug. 5, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventor: **Dennis Park**, San Francisco, CA (US)

(73) Assignee: **Apple Inc.**, Cupertino, CA (US)

(**) Term: **15 Years**

(21) Appl. No.: **29/890,962**

(22) Filed: **Apr. 28, 2023**

Related U.S. Application Data

(63) Continuation of application No. 29/755,745, filed on Oct. 22, 2020, now Pat. No. Des. 989,114, which is a continuation of application No. 29/684,789, filed on Mar. 24, 2019, now Pat. No. Des. 900,140.

(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The broken line showing of text and graphic elements forms no part of the claimed design.

1 Claim, 1 Drawing Sheet
